UNITED STATES PATENT OFFICE.

EBER R. CROFUT AND CHARLES L. GRIBBIE, OF NEWARK, NEW JERSEY.

WINDOW.

SPECIFICATION forming part of Letters Patent No. 295,362, dated March 18, 1884.

Application filed August 1, 1883. (No model.)

To all whom it may concern:

Be it known that we, EBER R. CROFUT and CHARLES L. GRIBBIE, citizens of the United States, residing at Newark, in the county of 5 Essex and State of New Jersey, have invented certain new and useful Improvements in Window-Sashes; and we do hereby declare the following to be a full, clear, and exact description of the invention, such as will enable others skilled in the art to which it appertains to 10 make and use the same, reference being had to the accompanying drawings, and to letters of reference marked thereon, which form a part of this specification.

This invention relates to improvements in window-sashes, and refers more particularly to those that are constructed so as to rotate upon a pivot in addition to the ordinary sliding movement, and is designed to facilitate the 15 cleaning of the windows from within, and thus avoiding the necessity of getting outside of the window and the danger common thereto.

The invention is also intended to more 20 effectually prevent the passage of air and moisture through the interstices of the frame of the windows as ordinarily constructed, and, further, to do away with all rattling and shaking 25 of the window-frames.

The invention consists in such construction, 30 combination, and operation of parts as will be hereinafter more fully described, and embodied in the claims.

Referring to the accompanying drawings, in 35 which similar letters of reference indicate like parts in each of the various figures, Figure 1 is a front elevation of a window-frame and sashes having attached thereto our device, the right-hand side of the lower sash being broken away, showing the relation of our improvement to the sash. Fig. 2 is an enlarged side 40 elevation, partly in section, detached from the sash. Fig. 3 is a plan view of the detached attachment, also enlarged; and Fig. 4 is a cross-section taken through line *x* of Fig. 1.

In carrying out our invention we employ a 45 supplemental piece, *a*, of the length of the window-sash from top to bottom, and of suitable thickness, having a recess therein to receive the working parts of our device. The 50 stile of the sash is also provided with a recess

corresponding to the recess in the supplemental piece, but of less depth. In addition to the supplemental piece *a*, we employ a metallic piece, *b*, preferably cylindrical, one end of which, *c*, may be reduced in diameter, having a thread thereon, the part *b* being about the length of the depth of the recess in the supplemental piece *a*, the central portion of said recess being cut away to receive said part *b*. 55

d is a locking-bar, which is contained within and is about the length of the recess in the supplemental piece, and passes through a slot or opening in the cylinder *b*, having the depression *d* therein, the use of which will be 60 described hereinafter.

e is a spring, which bears against the bar *d* near the extremities thereof, as shown. Said spring also passes through the slot *b'*, being secured therein by a pin, *f*, which passes 70 through the cylinder *b*, spring *e*, and bar *d*, serving to hold the parts in place. The pin *f* may be dispensed with, if desirable, the spring *e* being riveted to the part *b* instead.

g is a cap sunk within the stile of the sash, 75 having a female thread corresponding to the thread on *c*, and provided with screw-lugs or flanges *g'*, to secure the same, said lugs being placed, preferably, some distance from the outer edge of the cap at the bottom of the 80 recess in said stile, as shown in Fig. 1.

h is a small lever, shaped substantially as shown in Figs. 3 and 4, and pivoted within a slot, *b*, in the cylinder *b*, as indicated, one end of said lever bearing against the locking-bar *d* on the side opposite to the spring, and the other end projecting through the slot *b'*, and also through a corresponding slot in the supplemental piece *a*, as shown in Fig. 4. Pivoted to the supplemental piece *a* is a thumb 85 or finger piece, *i*, the short arm of which bears against the part of the lever *h* which projects through the slot in the piece *a*, the longer arm of said part *i* being adapted to be operated by the thumb or finger. 90

j is a plate secured to the supplemental piece *a*, having thereon the lug or projection *k*.

The cylindrical part *b* is provided with flanges *l*, for securing said part to the piece *a*, as indicated in Fig. 3. The cord to which the 100

weight is attached is secured to the supplemental piece *a*, as shown in Fig. 1.

The operation and relation of our device to the window frame and sashes are substantially as follows: The supplemental pieces *b* are connected with the window-sashes at the side by the screw *c*, which turns within the cap *g*, said cap being secured within the stile of the sash, as above described. The said pieces *a* slide within the ways or grooves of the window-frame, the joints between the said supplemental pieces and the window-sashes being placed outside of the stop-bead, so that the sashes will swing clear of the frame.

15 The normal position of the locking-bar is shown in Figs. 1 and 2, where, by the pressure of the spring *e*, it extends over the joint between the supplemental pieces *a* and the sash, into the recess in said sash, thus covering that portion of the joint and excluding air and moisture, and also by locking the sash prevents its turning and rattling. The depression *d* in the locking-bar allows said bar to extend into the recess in the sash, as will be evident by reference to Figs. 1 and 2.

20 The window may be unlocked by pressing the long arm of the thumb-piece *i* toward the outside of the frame. This acts upon the small lever *h*, which, in turn, presses the locking-bar *d* away from the sash and uncovers the joint, thus permitting the sash to be rotated upon the screw-pivot *c*.

25 Fig. 4 shows the locking-bar thrown back by the pressure of the lever *h*, and the position 30 of the thumb-piece *i*, when the bar is thus thrown back and held, is shown under line *x* of Fig. 1. The lug *k* on the plate *j* holds the piece *i* and prevents the bar *d* from springing back into the recess in the sash. The thumb-piece may be disengaged from the lug *k*, when 35 desired, by a slight movement of the thumb, as will be readily understood.

40 It will be evident from the construction of our device that the screws on one side of the sash must be right screws, and those on the other side left screws, in order that the sash may revolve. By this arrangement the screws not only act as pivots, but serve to tighten the sash when closed.

45 In order to more fully cover the joints between the sash and supplemental pieces *a*, where they are not covered by the locking-bar, we recess the said piece *a* at *a'* and *a''*, Fig. 3, and either attach to the sash or form integral 50 therewith projections *a'*, Fig. 1, which fit into said recesses, and thus break the joint and effectually prevent the entrance of air and moisture.

55 Our improvement may be applied to any window.

dow by cutting away a portion of the sash and substituting therefor the supplemental piece with its attendant parts *d b c*, &c., without otherwise disturbing the window frame and sashes.

The minor details of our invention may be varied without departing from the spirit thereof, as will be readily understood.

Having thus described our invention, what we claim, and wish to secure by Letters Patent, is—

1. The combination, with the sash or sashes of a window, having recesses (as *r*) therein, and projections *a'*, of a supplemental piece (as *a*) having a recess therein, and provided with recesses *a'* and *a''*, adapted to receive said projections *a'*, a locking-bar, *d*, and a spring, *e*, all substantially as and for the purposes set forth.

2. The combination, with the sash or sashes of a window, having a recess therein, and a cap (as *g*) provided with a thread, of a supplemental piece having a recess therein, a cylindrical piece, *b*, provided with a screw, *c*, and having a slot or opening, *b'*, therein, a locking-bar, *d*, having a depression, *d'*, said locking-bar moving within said slot *b'* in the piece *b*, and a spring secured to or within said piece *b*, all as set forth.

3. In a window attachment, the combination of a cylindrical piece (as *b*) having a slot, *b'*, therein, and provided with a screw, a locking-bar moving within said slot, a spring, and means for operating said locking-bar, all substantially as and for the purposes set forth.

4. In a window attachment, the combination of a cylindrical piece (as *b*) having a slot, *b'*, therein, and provided with a screw, a locking-bar moving within said slot, a spring, (as *e*), a lever, *h*, pivoted or attached to the cylindrical piece *b*, a thumb-piece, (as *i*), and a lug, *k*, all substantially as set forth.

5. In a window attachment adapted to be applied to the sashes of a window, the combination of a supplemental piece (as *a*) having a recess therein, a locking-bar, (as *d*), a spring, (as *e*), a device (as *b*) provided with a screw, *c*, and adapted to hold said bar and spring in operative relation, a lever, *h*, pivoted to said device *b*, a thumb-piece, *i*, and a cap, *g*, all substantially as and for the purposes set forth.

In testimony that we claim the foregoing we have hereunto set our hands this 21st day of July, 1883.

EBER R. CROFUT.
CHAS. L. GRIBBLE.
